UNITED STATES PATENT OFFICE

2,476,447

TWO-CYCLE SCAVENGING ENGINE,
SUPERCHARGINGCharles E. Lucke, New York, N. Y., assignor to
Worthington Pump and Machinery Corporation,
Harrison, N. J., a corporation of Delaware

Application March 23, 1946, Serial No. 656,634

12 Claims. (Cl. 123—65)

1

This invention relates to power plants, and more particularly to an internal combustion engine of the two cycle type.

An object of the present invention is to provide an internal combustion engine of the fuel injection, two cycle type wherein the construction is such as to secure a much higher power per cylinder than has heretofore been possible.

Another object is to provide an engine wherein the temperature of the metal parts and the lubricating oil film may be held within safely low temperature limits in spite of large increase in horsepower per cylinder.

Another object is to provide an engine which operates with a high degree of efficiency while developing a high horsepower per cylinder and at the same time keeping the temperature of the working parts within safe limits.

To attain the foregoing objects, mechanical means of great simplicity are provided for establishing conditions fundamental to the desired results. Increase of density of the air charge at the beginning of compression in the engine is the basis of a higher mean effective pressure and hence of increased horsepower per cylinder. Increase of scavenging air ratio, the ratio of volume of air to the piston displacement as mean pressure is increased through air density, is the basis of limiting rise of temperature of the metal parts in spite of the higher rates of heat generation.

The desirable results attained by the present invention are particularly useful in the simplest form of internal engine, namely, one in which air inlet and exhaust ports in a cylinder are opened and closed by a single piston without the aid of valves. Conventional engines of this class have scavenging pumps to supply air, delivering air at relative low pressure, because higher pressures can not be effectively used. This is due to the fact that when the piston closes the air port, the exhaust port is still open and the pressure can not rise substantially above that of the exhaust back pressure, normally but little above atmospheric.

In contradistinction to the conventional engine of the foregoing class, the present invention embodies a scavenging pump, preferably of the centrifugal type, single or multi-stage, capable of being operated at high enough speed to develop a relatively high air pressure, for example, two atmospheres absolute, more or less. To make use of such high air charging pressures, valved means are employed to raise the back pressure, so that the pressure at the beginning of compression may be substantially higher than the back pressure,

2

means being provided to always keep the air pressure at a value substantially in excess of the back pressure. The excess of the air pressure over the back pressure determines the quantity of air that flows through the cylinder while the inlet valve is opened, and the heat abstracted from the hot faces of the metal bounding the working charge will be increased as quantity of excess scavenging air is increased. Means are provided to control the excess scavenging ratio by increasing the excess of air pressure over the back pressure as back pressure is raised to increase the density of the cylinder charge and mean effective pressure. Thus, the increase in mean effective pressure by increase in air density is made safely usable by correspondingly increasing the internal face heat abstraction as these faces receive more heat. The scavenging pump is therefore also a supercharger.

The increase of mean pressure and horsepower per cylinder resulting from a higher back pressure with a correspondingly still higher air pressure, requires more horsepower to drive the scavenger-supercharger than otherwise, and this is subtracted from the horsepower developed by the engine proper because the air compressor is to be driven by the engine, and the efficiency may be expected to decrease as the net brake mean effective pressure rises. For some engine application purposes this is a real advantage and no serious disadvantage as it results in a light, compact and cheap engine, even if not of highest efficiency.

However, should high efficiency be also a desirable factor in the operating conditions, it can be obtained in the present engine without any changes, by merely adding an exhaust gas turbine with valved nozzles replacing the valved back pressure valve similarly operated and controlled. Increase of back pressure makes it possible to secure correspondingly increased horsepower from the turbine which is additive to that from the engine, thus raising the overall net efficiency by this increase of net horsepower with the same fuel consumption. In the present engine, the exhaust gas turbine is capable of safely utilizing the exhaust gas from the cylinder no matter how high the mean effective pressure in the cylinder because the exhaust gas temperature is not permitted to rise above a value that is safe for the turbine through control of the scavenging ratio by the maintained rise of excess air pressure over back pressure and corresponding excess of air with increase of engine load. The excess of air limits the temperature of exhaust gas by air dilution.

With these and other objects in view, as may appear from the accompanying specification, the invention consists of various features of construction and combination of parts, which will be first described in connection with the accompanying drawings, showing a power plant of a preferred form embodying the invention, and the features forming the invention will be specifically pointed out in the claims.

In the drawings:

Figure 1 is a diagrammatic view of an internal combustion engine in accordance with the present invention, with parts thereof shown in section for the purpose of illustration.

Figure 2 is a view taken from the position indicated by the line 2—2 of Figure 1.

Figure 3 is a view similar to Figure 1 but illustrating a pressure responsive control for maintaining an excess of air pressure over back pressure for all values of one of these pressures.

Figure 4 is a view similar to Figure 1 but illustrating a gas turbine arranged to utilize the exhaust gases from the engine.

Figure 5 is a view taken from the position indicated by the line 5—5 of Figure 4.

Figure 6 is an enlarged sectional view of the gas turbine nozzle arrangement.

Figure 7 is a view of the parts of Figure 6 but rotated 90° about a vertical axis.

Figure 8 is a diagrammatic view of a different form of air port arrangement.

Figure 9 is a diagrammatic view illustrating the inlet and exhaust ports extended all around the cylinder in two belts.

Figure 10 illustrates an engine wherein a valved exhaust port is utilized.

Figure 11 illustrates an engine embodying a valved inlet port.

Figure 12 illustrates an engine structure embodying two opposed pistons which may operate to open and close inlet and exhaust ports with the same timing difference as characteristic of Figure 11.

In the embodiment of the invention selected for illustration, Figure 1 illustrates an internal combustion engine 14 which is of the two cycle, compression ignition or Diesel type. This engine includes the usual cylinder 15 having a bore 16 within which the piston 17 is slidably guided, which piston is operatively connected with the crankshaft 18 in the usual manner. Oil fuel is introduced into the combustion chamber 19 through a fuel injection nozzle 20 such as is used for Diesel engine purposes. Exhaust ports 21 open from the combustion chamber 19 and communicate with an exhaust manifold 22, which in turn delivers the exhaust gases into an exhaust pipe or conducting means 23.

A scavenger-supercharger 24, which comprises a centrifugal air compressor, has its rotor shaft 25 geared to the crankshaft 18 to be driven thereby, the two shafts being drivingly connected by a gear train 26.

Scavenging and supercharging air flows from the machine 24 to the combustion chamber 19 through a pipe or air conducting means 27. A valve or throttle 28 is incorporated in the pipe 27 to control the flow of compressed air to the engine. The pipe 27 opens into an air manifold 29 which has communication with the combustion chamber 19 through air inlet ports 30. Pressure gauges 31 and 32 are provided for the manifolds 29 and 22, respectively.

The ports 21 and 30 are opened and closed by the piston 17, with the arrangement such that

the exhaust ports 21 are opened before and closed later than the inlet ports 30. All the ports 30 take air from the air manifold 29, and the valve or throttle 28 controls the air pressure in the manifold 29, which throttle may be operated manually or by the engine governor (not shown) so as to insure that the engine cylinder will always have sufficient air charge to completely burn all of the fuel injected in accordance with the load requirements, manually for variable speed engines and by the governor for constant speed engines, consistent with the fuel oil injected.

All the exhaust ports 21 deliver to the exhaust manifold 22, and a back pressure valve or throttle 33 is provided in the pipe 23, which valve may be opened or closed to control the back pressure in the exhaust manifold 22, as desired. An essential feature of the present invention is the maintenance of an excess of air pressure over the back pressure for all values of one of these pressures, and an increasing excess as the air pressure is raised for higher mean effective pressures to insure a correspondingly larger excess scavenging ratio to control the exhaust gas temperature and insure adequate internal cooling of the working parts. One mechanical means of accomplishing this is shown diagrammatically in Figure 1, the air throttle 28, manually operated or operated by a governor (not shown), controls the air supply to the air manifold 29, and for a given setting of the back pressure valve 33, opening of the air throttle valve 28 will raise the pressure in the air manifold 29, as may be indicated by the air pressure gauge 31.

In Figure 3 the back pressure valve 33 is actuated by a piston 34 slidably guided in cylinder 35. A rod 36 is fixed to a piston 34 and has one end extended to a position externally of the cylinder 35 for connection with a crosshead 37. One end of a link 38 is pivotally connected with the crosshead 37 and its other end is pivotally connected with a lever 39 attached to the back pressure valve 33.

A second cylinder 40 is connected in co-axial relationship with the cylinder 35 and contains a piston 41 which is fixed to the other end of the piston rod 36. Between the piston 41 and a stop 42 is interposed a compression spring 43 the tension of which may be changed through adjustment of a screw 44 which is threaded through one end of the cylinder 40 and arranged in engagement with the stop 42. A pipe or conducting means 45 communicates with the air manifold 29 and has a branch 46 which opens into the chamber 47 in the cylinder 35. The pipe 45 includes a second branch 48 which opens into the chamber 49 of the cylinder 40. Vents 50 are provided in cylinder 40 opposite the chamber 49 to permit free movement of the piston 41. A conduit or conveying means 51 leads from the exhaust pipe 23 and opens into the chamber 52 in the cylinder 35, with the pipe 51 having communication with the exhaust pipe at a point between the exhaust manifold 22 and the back pressure valve 33. Adjustable valves 53 and 54 are interposed in the conduit 45 on opposite sides of the branch 48 so that the flow of compressed air to the chamber 49 may be controlled or shut-off through the adjustment of the valve 53. The valve 54 is normally adjusted to vent compressed air to the atmosphere.

According to Figure 3 the air pressure acts on one side of the piston 34, while the back pressure acts on the opposite side of the piston 34,

with the spring 43 acting on the piston 41, tending to move the assembly to the left supplementing the force due to back pressure. The sum of these two forces being balanced by the air pressure, the air pressure must always be greater than the back pressure by an amount corresponding to the spring load which is adjustable.

The air pressure is also led to the chamber 49 which carries the spring 43, the joint adjustment of the valves 53 and 54 controlling the pressure in the spring containing chamber and adds to the spring load effective on the piston 41 at all times, but as the air pressure rises so also will the pressure in the spring containing chamber and the supplement to the spring load. In this manner the difference between the air pressure and back pressure will increase as air pressure rises, thus insuring that the excess scavenging ratio that controls internal cooling and exhaust gas temperature, will rise with increase of cylinder charge density, and mean effective pressure.

In Figures 4 and 5, a gas turbine 55 is associated with the engine 14. The exhaust gases delivered to the pipe or conducting means 23 are utilized for driving the turbine 55. In utilizing the exhaust gases for turbine driving purposes, the back pressure valve 33 is set in its wide open position or may be omitted.

Exhaust gases enter the turbine 55 through the chest 56, see Figure 6, and inlet valves 57 control the flow of gases through the passage 58 and to the nozzles of the turbine, the nozzle structure of the turbine being indicated generally at 59 in Figure 7. Since the inlet valves 57 are adjustable and each controls gas admission to a different set or section of nozzles, the effective nozzle area of the turbine may be regulated through adjustment of the valves. Each valve is opened by an independent cam 59 mounted on a camshaft 60, and the cams may be shaped to give any desired rate or sequence of opening. Rotation of the camshaft 60 imparts valve actuating motion to the cams 59, which rotation can be controlled manually or by automatic devices, an actuating lever 61 being illustrated in Figure 7 for imparting rotation to the camshaft.

The rotor of the turbine 55, shown fragmentarily at 62 in Figure 7 and as comprising wheels 63 arranged in operative relationship with the nozzle structure 59, drives the rotor shaft 64 of Figures 4 and 5. A gear train 65 drivingly connects the rotor shaft 64 with the crankshaft 18.

Figures 8 through 12 illustrate other two cycle port arrangements, some of which may be supercharged to some degree and in which excess scavenging may be secured also to some degree, but to all of these the present invention is also applicable as an improvement.

Figure 8 illustrates an engine cylinder 66 which is provided with an air inlet port 67 and a secondary air inlet port 68. The port 68 is arranged to be opened before and closed after the exhaust port 69, but is provided with a valve 70 which is forced to a closed position by pressure acting on its face when the cylinder pressure is higher than the air pressure.

In Figure 9, the inlet ports 71 and the exhaust ports 72 extend all around the cylinder 13 in two lines or planes, with the operation the same as in an engine structure of the type shown in Figure 1.

Figure 10 illustrates an engine cylinder 14 wherein a valve 75 is provided for exhaust port 76, while in Figure 11, a valve 77 is provided for

the air inlet port 78, the valves 75 and 77 allowing different timing relations between exhaust and inlet. The same timing difference may be obtained in an engine structure such as that shown in Figure 12, wherein two opposed pistons 79 are employed, and in which the inlet ports 80 and the exhaust ports 81 are located at opposite ends of the combustion chamber 82.

It will be understood that the invention is not to be limited to the specific construction or arrangement of parts shown, but that they may be widely modified within the invention defined by the claims.

What is claimed is:

1. The method of air charging the cylinders of a two cycle piston type internal combustion engine as power requirements increase which comprises charging the cylinders with compressed air at the beginning of the compression stroke while exhausting burned gases from the cylinders and increasing the pressure of the charging air while increasing at a lesser rate the resistance to exhaust flow of the burned gases, said resistance being regulated so that the back pressure of exhaust gases is less than the pressure of charging air.
2. In a charging system for the cylinders of a two cycle piston type internal combustion engine the combination of exhaust conduits connected to the cylinders for exhausting burned gases therefrom, first means for delivering pressure air to the cylinders, valve means in said exhaust conduits for resisting the flow of burned gases therethrough, control means for operating the valve means, and means operatively connecting the first means to the control means so that variations in the pressure of the air being delivered to the cylinders actuates the control means, said control means being constructed and arranged so that increases in air pressure increase the resistance of the valve means and the back pressure of exhaust gases due to said resistance remains less than the pressure of the air.
3. In a charging system for the cylinders of a two-cycle piston type internal combustion engine as claimed in claim 2 wherein the control means is constructed and arranged to increase the resistance and thus the back pressure at a lesser rate than the rate of increase of air pressure.
4. In a charging system for the cylinders of a two cycle piston type internal combustion engine the combination of exhaust conduits connected to the cylinders for exhausting burned gases therefrom, valve means in said conduits for resisting the flow of burned gases therethrough, pressure responsive means for actuating said valve means to increase the resistance as the pressure thereon is increased, means for delivering charging pressure air to the cylinders, and means operatively connecting said last mentioned means to the pressure responsive means so that pressure air actuates the same, said pressure responsive means being constructed and arranged to regulate the resistance of the valve means so that the back pressure of the exhaust gases is less than the pressure of the air.
5. In a charging system for the cylinders of a two-cycle piston type internal combustion engine as claimed in claim 4 wherein the pressure responsive means is constructed and arranged to increase the resistance and thus the back pressure at a lesser rate than the rate of increase of air pressure.

6. In a charging system for the cylinders of two-cycle piston-type internal combustion engines the combination of exhaust conduits connected to the cylinders for exhausting burned gases therefrom, valve means in said conduits for resisting the flow of burned gases therethrough, pressure responsive means for actuating said valve means to increase the resistance as the pressure thereon is increased, means for delivering charging pressure air to the cylinders, means for delivering charging pressure air from said pressure air delivering means to said pressure responsive means, means for delivering exhaust gases from said exhaust conduits to said pressure responsive means whereby the pressure responsive means will be under opposed pressure of charging pressure air and exhaust gas pressure, pressure exerting means cooperating with the exhaust gases in said pressure responsive means so that the back pressure of the exhaust gases is less than the pressure of the charging air.

7. In a charging system for the cylinders of two-cycle piston-type internal combustion engines the combination of exhaust conduits connected to the cylinders for exhausting burned gases therefrom, valve means in said conduits for resisting the flow of burned gases therethrough, pressure responsive means for actuating said valve means to increase the resistance as the pressure thereon is increased, means for delivering charging pressure air to the cylinders, means for delivering charging pressure air from said pressure air delivering means, means for delivering exhaust gases from said exhaust conduits to said pressure responsive means, said pressure responsive means embodying differential areas the larger of which is exposed to opposing pressures of charging air and exhaust gases and the smaller of which is exposed to pressure of charging air, the charging air pressure on the smaller area cooperating with the exhaust gas pressure on the larger area in opposition to the charging air pressure on the larger area.

8. In a charging system for the cylinders of two-cycle piston-type internal combustion engines the combination of exhaust conduits connected to the cylinders for exhausting burned gases therefrom, valve means in said conduits for resisting the flow of burned gases therethrough, pressure responsive means for actuating said valve means to increase the resistance as the pressure thereon is increased, means for delivering charging pressure air to the cylinders, means for delivering charging pressure air from said pressure air delivering means to said pressure responsive means, means for delivering exhaust pressure air delivering means to said pressure responsive means, said pressure responsive means embodying differential areas the larger of which is exposed to opposing pressures of charging air and exhaust gases and the smaller of which is exposed to pressure of charging air, the charging air pressure on the smaller area cooperating with the exhaust gas pressure on the larger area in opposition to the charging air pressure on the larger area, and tensioned pressure exerting means exerting pressure on said smaller area in cooperation with the pressure of charging pressure air thereon, whereby the resistance of the valve means will be regulated so that the back pressure of the exhaust gases is less than the pressure of charging air and the back pressure of the exhaust gases will be increased at a lesser rate than the increase of pressure of charging air.

5 9. In a charging system for the cylinders of a two-cycle piston-type internal combustion engine as claimed in claim 8, means for adjusting the tension of said tensioned pressure exerting means to vary the ratio of difference in increases in back pressure and pressure of charging air.

10 10. The method of air charging the cylinders of a two-cycle piston type internal combustion engine as power requirements for a given speed increase, which comprises charging compressed air into the cylinders while exhausting burned gases therefrom and simultaneously increasing both the pressure of the charging air and the back pressure of the exhaust gases while maintaining the back pressure less than the pressure of the charging air and increasing the pressure of the charging air at a greater rate than the increase in the back pressure.

11 11. In a charging system for the cylinders of two-cycle piston-type internal combustion engines the combination of exhaust conduits connected to the cylinders for exhausting burned gases therefrom, valve means in said conduits for resisting the flow of burned gases therethrough, 20 pressure responsive means for actuating said valve means to increase the resistance as the pressure thereon is increased, means for delivering charging pressure air to the cylinders, means for delivering charging pressure air from said pressure air delivering means to said pressure responsive means, means for delivering exhaust gases from said exhaust conduits to said pressure responsive means, said pressure responsive means embodying differential areas subjected to the 25 pressure of charging air and pressure of exhaust gases plus pressure of the charging air whereby the resistance of the valve means will be regulated so that the back pressure of the exhaust gases is less than the pressure of charging air and the 30 back pressure of the exhaust gases will be increased at a lesser rate than the increase of pressure of charging air.

12 12. A charging system for the cylinders of a two-cycle piston-type internal combustion engine as claimed in claim 11 including tension pressure exerting means for exerting pressure on one of said differential areas and means for adjusting the tension of said tension pressure exerting means to vary the ratio of difference in increases in back pressure and pressure of charging air.
